UNITED STATES PATENT OFFICE.

JOSEPH W. BLOWER, OF COLUMBUS, OHIO.

RAILWAY-TRACK CONSTRUCTION.

981,971.

Specification of Letters Patent.

Patented Jan. 17, 1911.

Application filed November 10, 1910. Serial No. 591,585.

To all whom it may concern:

Be it known that I, JOSEPH W. BLOWER, a citizen of the United States, residing at Columbus, in the county of Franklin and 5 State of Ohio, have invented certain new and useful Improvements in Railway Track Construction, of which the following is a specification.

My invention relates to the improvement 10 of railway track construction, and the objects of my invention are to provide an improved substantial construction of railway track, wherein the necessity of employing fish plates bolted to the track rails, is obviated; to provide improved means for securing the track rails in connection with the ties, and for connecting sections of the track rails; to provide means whereby ordinary railway spikes may be employed in connecting track rails with metal ties, and to produce other improvements the details of 20 which will be more fully pointed out herein-after. These objects I accomplish in the manner illustrated in the accompanying drawings, in which...

Figure 1 is a plan view of a section of a railway track having my improved construction, Fig. 2 is an enlarged transverse section on line $x-x$ of Fig. 1, and, Fig. 3 is a side elevation of portions of track-rails, and my improved track holding members being shown in cross section on a line central of the widths of the track rails.

Similar numerals refer to similar parts 35 throughout the several views.

1 represent metal railway track ties, which are preferably formed of ordinary T-rails or track rail sections, although it will be obvious that a metal tie in the form of a bar 40 having its opposing sides channeled, might be employed.

2 represent track rail sections which are designed to bear upon the heads or upper sides of the ties 1 in the usual manner.

45 One of the ties 1 is employed beneath each joint of the track rails 2, as well as between solid portions of the separate track sections. Where the ends of the track rails meet above a tie 1, I provide on opposite sides of the tie beneath the track rails, followers or 50 filling blocks 3, so shaped on their inner sides as to conform to the outlines of the sides of the ties. The upper sides of the blocks 3 thus arranged are flush with the upper sides of the ties, said blocks thus 55 forming individual supports for the rail sec-

tions 2. In order to effectively connect the opposing blocks 3, I provide a suitable bolt or equivalent fastening device 4, which passes through said blocks and through an opening in the web of the tie. Formed in each of the blocks 3 on opposite sides of the center of its length, are rectangular openings 5, the upper portions of the inner walls of these openings being substantially vertical, while the outer wall of each of the openings is inclined as indicated at 6, resulting in the production of a gradual decrease in the length of the opening toward its lower end.

In securing the adjoining ends of two track rail sections upon a tie, I preferably employ the ordinary forms of railway spikes such as are indicated at 7, but prior to the insertion of each spike, I insert within the upper portion of each of the openings 5, a block 8 preferably of wood or other yielding material, between which block and the inner end of the opening 5, is driven downwardly the shank of the spike 7, the projecting head of the spike thus being driven into engagement with the projecting base flange of the track rails. By this operation, it will be understood that the spike is wedged tightly between the wooden block 85 and the body of the block 3, in which the opening 5 is formed. In order to insure a proper wedging of the spike in this position, and prevent the block 8 from being driven downward through the opening 5, I have inclined the outer wall of the opening 5, thus insuring a wedging action of both the spike and block.

Where the ties are laid beneath the track rails and between the ends of a track rail section it is considered unnecessary to use more than one of the blocks 3, this construction being more fully illustrated in Figs. 1 and 3 of the drawing.

Heretofore one of the difficulties attending the employment of metal ties, has been the necessity of forming vertical key or spike openings in the ties and these openings had to be necessarily spaced apart, so as to accommodate track rail base flanges of different widths. In case of a deviation in the width of the track rail base flange, it is obvious that the employment of the oblong openings 5 and binding blocks 8 of different thicknesses will overcome the difficulty above referred to.

It is obvious that in the construction of a

railway track, such as herein described, the track rails will be at all times maintained in their proper relative and parallel positions and an exceedingly strong structure 5 will be produced.

From the foregoing description, it will be seen that simple and efficient means are herein provided for accomplishing the objects of the invention, but while the elements shown and described are well adapted 10 to serve the purposes for which they are intended, it is to be understood that the invention is not limited to the precise construction set forth, but includes within its 15 purview such changes as may be made within in the scope of the appended claims.

What I claim, is—

1. In a railway track construction, the combination with a plurality of metallic 20 ties, of a block bearing against the side of each of said ties, elongated openings formed in each of said blocks on opposite sides of its center, filling members adapted to be inserted in the outer ends of said block 25 openings, and a track rail bearing upon said ties and said blocks, the spaces between said filling members and track rails adapted to receive railway spikes.

2. In a railway track construction, the 30 combination with a plurality of metallic ties, of a block bearing against the side of

each of said ties, elongated openings formed in each of said blocks on opposite sides of its center, the outer wall of each of said openings having its lower portion inclined 35 inwardly, filling members adapted to be inserted in the outer ends of said block openings, and a track rail bearing upon said ties and said blocks, the spaces between said filling members and track rails adapted to receive railway spikes.

3. In a railway track construction, the combination with a plurality of metallic ties having longitudinally channelled side portions, of blocks embracing opposite sides 45 of said ties and connected with each other through said ties, track rails bearing upon said ties and blocks, a pair of elongated openings in each of said blocks on opposite sides of the track rail flanges, filling members 50 adapted to be inserted in the outer portions of said block openings, and spikes having enlarged heads, the shank portions of said spikes being adapted to be driven downward between said filling members and the body of the block.

In testimony whereof I affix my signature in presence of two witnesses.

JOSEPH W. BLOWER.
